[57] **CLAIM**

The ornamental design for a tip for christmas tree
stringing tool, as shown.

DESCRIPTION

FIG. 1 is a perspective view of a tip for Christmas tree
stringing tool showing my new design mounted upon a
shaft shown in broken line;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is a bottom plan view thereof.

The broken line of FIG. 1 showing the shaft is for illus-
trative purposes and forms no part of the claimed de-
sign.
